(57) **CLAIM**

The ornamental design for a light guiding plate having V-shaped notches, as shown and described.

DESCRIPTION

FIG. 1 is a perspective view of the light guiding plate having V-shaped notches showing a new design;

FIG. 2 is another perspective view thereof;

FIG. 3 is a front view thereof shown in FIG. 1;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a sectional view of the section-line 9-9 shown in FIG. 7;

FIG. 10 is an enlarged view of the area 10 shown in FIG. 1; and,

FIG. 11 is an enlarged view of the area 11 shown in FIG. 9. The broken lines shown in the drawings illustrate environmental structure and form no part of the claimed design.

1 Claim, 11 Drawing Sheets
